No. 681,046.

Patented Aug. 20, 1901.

H. ELINOFF.

LEDGER OR ACCOUNT BOOK.

(Application filed Aug. 16, 1900.)

(No Model.)

THE NORRIS PETERS CO., PHOTO-LITHO., WASHINGTON, D. C.

UNITED STATES PATENT OFFICE.

HARRY ELINOFF, OF PITTSBURG, PENNSYLVANIA.

LEDGER OR ACCOUNT-BOOK.

SPECIFICATION forming part of Letters Patent No. 681,046, dated August 20, 1901.

Application filed August 16, 1900. Serial No. 26,998. (No model.)

To all whom it may concern:

Be it known that I, HARRY ELINOFF, a citizen of the United States of America, residing at Pittsburg, in the county of Allegheny and State of Pennsylvania, have invented certain new and useful Improvements in Ledgers and Account-Books, of which the following is a specification, reference being had therein to the accompanying drawings.

10 This invention relates to certain new and useful improvements in ledgers or account-books, and more particularly to that class of ledgers containing removable pages or leaves.

The herein-described invention has for one 15 object to construct a ledger or account-book of this character wherein any number of leaves may be easily removed therefrom and again inserted in proper position. Furthermore, the invention aims to construct a book 20 of this class wherein any page in the book may be easily removed without removing any of the other adjacent or consecutive pages.

The present invention has for its still further object to construct an attachment of the 25 above-described character that will be extremely simple, strong, durable, and comparatively inexpensive to manufacture; furthermore, one that may be readily opened and closed and easily handled.

30 With the above and other objects in view the invention consists in the novel combination and arrangement of parts to be herein-after more fully described, and specifically pointed out in the claims.

35 In describing the invention in detail reference is had to the accompanying drawings, forming a part of this specification, and wherein like numerals of reference indicate corresponding parts throughout the several 40 views, in which—

Figure 1 is a perspective view of my improved ledger or account-book, showing the same in an opened position. Fig. 2 is a perspective view of the frame, showing the hinged sections. Fig. 3 is a vertical sectional view of the back of the book when in a closed position. Fig. 4 is a top plan view of the locking mechanism with the top plate removed therefrom. Fig. 5 is a side elevation with 45 the top plate in proper position. Fig. 6 is a perspective view of the mechanism as shown

in Fig. 4. Fig. 7 is a side view, partly in section, of the semicircular hooks.

In the drawings the reference-numeral 1 indicates the back of the book, and 2 3 indicate the hinged sections, which are centrally connected, as shown at 4, by a rod 5, extending from end to end of the hinged portion. 55

The reference-numerals 6 indicate standards, which are rigidly secured to the section 3, said standards being preferably hollow and provided with a series of teeth 7. The lower plate of the section 3 is provided at each end with a semicircular guide 8, said guides being tubular in form and adapted to receive semi-circular rods 9, the latter being rigidly secured to the section 2. 60

The reference-numerals 10 indicate the pages or leaves of the book, having apertures for the reception of the standards 6. 70

The reference-numerals 12 13 indicate, respectively, the upper and lower plates forming the casing for the locking mechanism, which is suitably spaced apart by means of end blocks 14, secured between the plates by 75 screws 15. In said casing is arranged the locking-bars 16 17, said locking-bars being preferably Z-shaped and operating in close proximity to each other. The locking-bars are slotted, as at 18 19, to receive the 80 guide-pins 20 for holding the bars in proper position and in proper relation to each other. The ends of the locking-bars are wedge-shaped, as shown at 21, and adapted to engage in the teeth 7 of the standards 6. The 85 said bars are spring-pressed by means of springs 22 23, which serve to normally engage the wedge ends 21 of the bars with the teeth 7. The locking-bars are still further provided with notches 24 25 to receive a key, 90 which key is adapted to pass through a suitable opening 26, formed in the upper plate 12. The upper and lower plates 12 13 are also provided with apertures to receive the standards 6. On the inner face of the section 2 95 are secured eyes 28, which are adapted to receive semicircular hooks 29, the latter being swiveled thereto, so that the free ends of the hooks may be inserted in the standards 6.

The operation of my improved ledger is as 100 follows: When it is desired to remove a certain page from the ledger or book, the key is

inserted to operate the locking-bars, and when partially rotated will tend to operate both locking-bars inwardly, thereby retracting the same and releasing the wedge ends 5 from engagement with the teeth of the standards. The semicircular hooks 29 are then released from engagement with the standards, which will permit the casing carrying the locking-bars to be easily removed there-
to from. These hooks are then again placed in proper position and the ledger is turned to the page that it is desired to remove, and the pages preceding the same are turned over upon the semicircular hooks. When this has been 15 done, these hooks are again disengaged from the standards, the page removed, the hooks again engaged with the standards, and the pages that were held by the hooks again returned to their position on the standards.
20 The hooks are then again disengaged, and as these hooks are swiveled in the eyes 28 they may be readily turned downwardly, so that the back may be closed. After the hooks 29 have been thus disengaged the casing carry-
25 ing the locking mechanism is again placed on the standards 6 and the pages locked in position.

It will be noted that various changes may be made in the details of construction with-
30 out departing from the general spirit of my invention.

Having thus fully described my invention,

what I claim as new, and desire to secure by Letters Patent, is—

1. In combination in a ledger, two hinged 35 sections, upright standards secured in one of said sections, locking-plates adapted to engage said standards, and hooks attached to the other hinged section and adapted to engage said standards, substantially as set forth. 40

2. In a ledger of the character described, the combination of two hinged sections, two standards secured to one of said sections, spring-pressed locking-bars adapted to normally engage said standards, and swiveled 45 hooks arranged in the other hinged section and adapted to engage in the upper portions of said standards, substantially as set forth.

3. In a ledger of the character described, the combination of two hinged sections, hollow notched standards arranged in one of said sections, perforated plates forming a casing carrying locking-bars adapted to engage said standards, swiveled hooks arranged upon the other hinged section, and suitable 55 guides secured at each end of said hinged sections, all parts being arranged and operating substantially as shown and herein specified.

In testimony whereof I affix my signature in the presence of two witnesses.

HARRY ELINOFF.
